J. KAHN

LOOSE LEAF BINDER

Filed Sept. 22, 1923

Witness:

Inventor,
Joseph Flann,
By off. Bulkley & Scott, Phys.

UNITED STATES PATENT OFFICE.

JOSEPH KAHN, OF CHICAGO, ILLINOIS.

LOOSE-LEAF BINDER.

Application filed September 22, 1923. Serial No. 664,154.

To all whom it may concern:

Be it known that I, JOSEPH KAHN, a citizen of the United States, and a resident of Chicago, in the county of Cook and State 5 of Illinois, have invented certain new and useful Improvements in Loose-Leaf Binders, of which the following is a specification.

This invention relates to improvements in 10 loose-leaf binders, and more particularly to the form of binder disclosed in my prior application filed May 23rd, 1922, Serial No. 563,512, and characterized by the use of hook-like fastening members mounted on 15 one of the binder covers and engaging the adjacent ends of binding posts fixed to the other binder covers.

The object of the invention is to provide 20 a new and useful binder, including in its construction a simple, substantial, and positive locking mechanism, hereinabove referred to as hook-like fastening members, together with means for guiding the posts into registering relation for locking, there- 25 by facilitating the operation of the locking mechanism.

Further and other advantages will be brought out in connection with the description which follows, and in connection with 30 the accompanying drawings, wherein—

Figure 1 is a perspective view of the binder in open position, showing the locking mechanism.

Figure 2 is an enlarged fragmentary view 35 of a single lock in position for locking.

Figure 3 is a detail view in vertical section taken on line 3, 3 of Figure 2, and

The Figure 3^a is a detail view similar to Figure 3, but showing the locking member 40 connected with the post, and

Figure 4 is a view similar to Figure 2, showing the posts in locked position.

A loose-leaf binder, in the typical form, consists of cover members 1 and 2 joined 45 together by a back portion of section 3 to which the cover members are hinged in the manner long practiced in the art of book-making. Between the cover members are held the binder sheets or leaves 4, to any 50 thickness not to exceed the width between covers, said leaves being held in place by means of transverse binding posts 5, 5 extending between covers and located near the back section 3. Holes punched in the 55 marginal portion of the leaves are engaged by the posts.

In the binder, herein illustrated, the cover members are stiff, being made of one or more plies of card board covered with leather or other binding material. The 60 back section 3 is also stiff, although it may be relatively flexible or limp, if so desired. As shown in Fig. 2, the posts 5, 5 are cylindric rods fixed or anchored in a stiff rail 6, extending transversely of the bottom 65 cover 2, parallel with and adjacent to the flexible hinge connecting said cover and back section 3. The rail 6 is preferably embedded or inlaid in the body of the cover. In the free ends of the posts are formed 70 eyes 5^a extending diametrically there-through in alignment with each other.

Along the inner edge of the top cover 2 and adjacent to the connecting hinge is a shallow metallic casing 7 which encloses 75 and supports the locking members and operating parts, the former being movable into and out of engagement with the eyes 5^a of the posts 5.

The casing 7 is preferably constructed in 80 two parts, namely, a flat bearing plate 8, and a flanged cover plate 9, secured to said bearing plate by suitable fastening means. The marginal flanges 9^a of the cover plate 85 abut against the bearing plate, spacing them apart and forming a shallow chamber there- 90 between. Along the inner edge of the bearing plate is a tubular bead 10, which projects bodily beyond the hinged edge of the cover 1, and, when the binder is closed, occupies a position immediately over the 95 ends of the posts 5, 5. The tubular bead is provided with notches or recesses 10^a, 10^a adapted to register with the free ends of the posts 5, 5 and permit locking action be- 100 tween the eyes 5^a, 5^a and the locking hooks, hereinafter to be described. Along the op- 105 posite side of the casing 7, the bearing plate 8 is extended beyond the cover plate, forming a flange 11 which extends between the layers of card board forming the cover 1, the outermost layer extending the full width of the casing and the innermost layer ter- 110 minating in abutting engagement against the edge of the cover plate 9, as clearly shown in Fig. 2. Several rivets 12, 12 are passed through the flange 11 and the outer- 115 most layer of card board, thus firmly anchor- 120 ing the plate 8 in place. In construct- 125 ing the binder the casing is embedded in the cover so that the inner surfaces of both 130 are flush, the casing being covered over by

the layer of finishing material which is applied after it has been secured in place.

Pivottally mounted upon the bearing plate 8 is a pair of similar fastening members or hooks 13. Each fastener or hook is pivoted at 14 intermediate its ends, and extends transversely of the plates in flatwise contact therewith, the hooked end portion 13^a extending substantially in line with the tubular bead 10, as clearly shown in Fig. 3. The movement of the fastening members imparted by actuating parts engaging the rounded head 13^b at the inner end of each, carries the outer hook portion longitudinally across the notches 10^a, the extremity thereof engaging the opening in the tubular bead formed by the notch. On the opposite side of the notch the tubular bead is slotted lengthwise as at 10^b, thereby providing a supporting or guide slot for the shank of the hook.

The relation of the fastening members and the posts 5 is such that the movement of the former acts to engage and disengage the eyes 5^a at the free ends of the latter when the ends of the posts are brought into registering relation with the notches 10^a of the tubular bead 10. In this position the ends of the hooked portions are brought into alignment with the eyes of the posts so that in the endwise movement of the fastening members, the ends thereof pass through the eyes and into the open ends of the tubular bead beyond, thus providing hinges or pins upon which the free ends of the posts may turn in the opening and closing of the binder.

The means for actuating the fastening members comprise a flat endwise movable bar 15 mounted between the plates 8 and 9 and held from lateral displacement by guides 16 struck up from the metal of the bearing plate 8. Along the inner edge of the strip 15 are provided notches 17, which receive the rounded ends 13^b of the fastening members 13 so that the shifting of the bar endwise actuates the fastening members into locking and releasing positions. The endwise movement of the strip is limited by longitudinal slots 15^a through which pass the rivets 15^b, connecting the top and bottom plates 8 and 9.

Several means may be adopted for manually operating the strip or sliding bar 15, the simplest being perhaps a handle 18, formed by bending one end of the bar at right angles and projecting through a recess 2^a in the cover 2.

Integral with the sliding bar 15 and adjacent each of the locking members 13, is an arm 19, extending at right angles thereto toward the tubular bead 10 and terminating in a sleeve 20, surrounding the same adjacent each notch 10^a thereof and having sliding engagement therewith. In the end of

the sleeve adjacent the notch, is a slot or recess 21, opening or facing outwardly and away from the hook members. Diametrically opposite the slot or recess 21 in the sleeve 20 is a corresponding slot 21^a of substantially the same length, but slight narrower. This slot 21^a is provided to allow the movement of the sleeve 20 with respect to the hook 13. The slot is slightly deeper than the width of the notch, and of about the same width as the diameter of the tubular bead so that when the sleeve is shifted endwise over the notch, the slot forms an opening into which the end of the post 5 may be guided into position for locking, that is, with the eye 5^a thereof registering with the end of the hook member, fastened at the entrance of the notch and in readiness to pass through the eye.

The function of the sleeve will be clearly understood from the following: The locking of the post ends is accomplished by shifting the bar 15 endwise to the left (Figure 1) thus swinging the hooks to throw the ends in the opposite direction across the notches 10^a, and through the eyes 5^a of the posts which have been brought into register with the notches in the tubular bead. The sleeves 20 are so located on the bar 15 that when the latter is shifted to actuate the hooks into locking position, the same are carried to one side of the notches leaving them uncovered. So, also, when the bar is shifted to the right to effect the unlocking of the posts, the sleeve moves to the right and over the notches and remain in that position until the next locking operation. It follows therefore, that the sleeves function only while the device is unlocked, its primary function being to assist in bringing the post ends into position for locking, by forming an opening or guide slot into which said ends can be inserted. Thus the notches 10 are temporarily converted into sockets, which hold the eyes 5^a in alignment with ends of the hooks, until the locking movement is started, whereupon the sleeves are carried into inoperative position, thus allowing the ends of the posts to turn freely on the hooks. In the absence of the sleeves it is difficult to properly locate the post ends within the notches, and at the same time operate the locking device. By providing a positive guide, however, it is only necessary to insert the end of the post in the opening, and the proper positioning is assured.

Another advantage of the sleeves is this: It is to be noted that the slots 21 are so located in the sleeves that it is necessary to hold the top cover upright and at right angles to the bottom cover, or parallel to the posts in order to insert the post ends into the notches, (Figure 3). Furthermore, when the locking has been completed and the sleeves are shifted to one side of the notches,

the swinging of the top cover out of vertical position revolves the sleeve sufficiently to throw the slots 21 out of alignment with the ends of the posts, with the result that the sleeves cannot be shifted until the cover is again brought into its initial position. Thus, the sleeves being locked against movement, the entire locking mechanism is rendered inoperative so that it follows that the sleeves act as locking members preventing accidental unlocking of the binder in all positions except the one indicated. Incidentally this feature offers a considerable degree of protection against the removal of sheets by unauthorized persons, for unless they are familiar with the arrangement, their endeavors would be hampered, if not completely frustrated. Similarly the slots may be formed in the sleeves so that the insertion of the post ends may take place only when the binder is open flat, as in Figure 1.

The invention herein disclosed fulfills a simple, yet effective purpose, and provides a useful and practical element in conjunction with an otherwise serviceable locking device for binders.

The various details of design and structure herein disclosed may be variously modified without departing from the spirit of the invention, and therefore I do not wish to be limited except in so far as the invention is defined in the appended claims.

I claim:

1. A binder comprising hinged together covers, a post secured to one cover, a locking member secured to the other cover, and adapted for locking engagement with said post, and a shiftable member co-acting with said locking member to guide the post into locking position.

2. A binder comprising hinged together covers, a post anchored in one of said covers, a locking member mounted on the other cover member, means for actuating said locking member into and out of locking engagement with said post and a member operatively connected with said locking member actuating means for guiding the end of said post into position for engagement with said locking member.

3. A binder comprising hinged together covers, a post anchored in one of said covers, a locking member mounted on the other of said covers and shiftable transversely of said post to engage the end thereof, a fixed guide member having a notch to receive the end of said post for locking, and a shiftable guide member co-acting with said locking member to guide said post into said notch and in position for locking.

4. A binder comprising hinged together covers and back, a post secured to one cover, a locking member pivotally mounted on the other cover and having an end portion adapted to engage an eye in the end of said

post, a fixed guide for said locking member, having a recess to receive the end of said post and a shiftable guide member operative to present an opening to receive the end of said post when said locking member 70 is in unlocking position.

5. A binder comprising hinged together covers, a post secured to one of said covers, a tubular bead fixed to the other cover and provided with a recess adapted to receive the 75 end of said post, a locking member shiftable longitudinally of said flange, and across said recess, and a sleeve shiftable on said flange, and having an opening adapted in one position of the sleeve to register with 80 said notch, and to be positioned in alignment with said post.

6. A binder comprising hinged together covers, a post secured to one of said covers, a hooked locking member pivoted on the 85 other cover and adapted to engage an eye in the end of said post, a tubular guide for the end of said locking member, said posts being adapted to be positioned with its eye 90 in alignment with said tubular bead and a sleeve slidable on said flange and provided with an opening thereon, said sleeve being shiftable simultaneously with said locking member to present said opening to said post for guiding the same into position 95 for locking.

7. A binder comprising hinged together covers, a post secured to one of said covers, a hooked locking member pivoted on the 100 other cover and adapted to engage an eye in the end of said post, a tubular flange fixed at the edge of said cover and having a notch to receive the end of said post, and a sleeve slidable on said flange and provided with a slot adapted in the shifting 105 of said sleeve in one direction to register with said notch, and to be positioned in alignment with said post in a predetermined position of said cover.

8. A binder comprising hinged together 110 covers, a post secured to one cover, a locking member of hooked form pivotally mounted on the other cover, a tubular flange fixed to said last mentioned cover and forming a guide for the end of said locking member, a sleeve slidable on said tubular flange and in operative connection with said locking member, said sleeve having a slot in one end thereof, adapted to register with a recess in said tubular flange and to form 115 120 a guide opening thereto for said post, said sleeve being shifted out of guiding position as said locking member engages said post.

9. A binder comprising hinged covers, a 125 post secured to one of said covers, a locking member mounted on the other cover and adapted for locking engagement with the free end of said post, a fixed guide member for positioning said post in longitudinal 130

alignment with said locking member, and a shiftable guide member operatively connected with said locking member for positioning said post in transverse alignment with said locking member, said last mentioned guide member being moved into operative position in the unlocking movement

of said locking member, and out of operative position in the locking movement of said locking member.

In witness whereof, I hereunto subscribe my name this 19 day of September, A. D., 1923.

JOSEPH KAHN.
